(57) **CLAIM**

The ornamental design for a combined computer and video camera, as shown and described.

DESCRIPTION

FIG. 1 is a perspective view of a combined computer and video camera showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another right side elevational view, wherein the camera is in a first moving condition;

FIG. 9 is yet another right side view thereof, wherein the camera is in a second moving condition.

FIG. 10 is a second embodiment perspective view of a combine computer and video camera;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a another left side view, wherein the camera is in a first moving condition; and,

FIG. 18 is yet another left side view thereof, wherein the camera is in a second moving condition.

The portions of the article in broken lines are shown for illustrative purposes only and form no part of the claimed design.
